FOLDABLE METAL AWNING

Nicholas L. Etten, Cedar Falls, Iowa

Application June 5, 1951, Serial No. 230,048

13 Claims. (Cl. 160—62)

1

This invention relates to a foldable metal awning and more particularly to an easily installed metal awning operable from a compact folded position to an extended position affording great protection from elements which is strong and durable in construction and which is readily and economically manufacturable.

Conventional foldable awnings such as those constructed of canvas and the like are generally quite flimsy, are susceptible to damage by high winds and wear out quickly. In addition, such awnings, in order that their useful life be prolonged, must be taken down, stored, and put up annually. Further, such awnings are generally not attractive in appearance in their retracted or closed position.

One object of the present invention is to provide a foldable awning of a strong metallic construction which will resist high winds and which will be very durable.

Another object of the present invention is to provide a foldable metal awning which can be easily and economically manufactured.

A further object of the present invention is to provide an improved, readily operated mechanism for retracting and extending a foldable awning.

Still another object of this invention is to provide a foldable metal awning which is attractive in appearance in both the retracted and extended positions.

A still further object of the present invention is to provide an awning having improved ventilation structure.

A feature of the present invention is in the provision of an awning top including foldable sections which can be smoothly operated between a compact folded position and an extended position affording great protection from the elements.

Another feature of the present invention is in the provision of a metallic awning having a foldable top and extendible side panels connected to the foldable top and operable therewith.

A further feature of the present invention is in the provision of an improved compact bevel gear operating mechanism for a foldable awning.

Still another feature of this invention is in the provision of an improved louvered awning panel construction affording ventilation openings and preventing accumulation of hot air below the awning.

Other objects, features and advantages of the present invention will become more apparent from the following detailed description taken in conjunction with the accompanying drawings in which:

2

Figure 1 is a perspective view of an awning constructed in accordance with the principles of the present invention mounted on a window frame and disposed in extended position;

5 Figure 2 is a perspective view of the awning of Figure 1 in retracted or folded position;

Figure 3 is a sectional view, on an enlarged scale, taken substantially along line III—III of Figure 1;

10 Figure 4 is a side elevational view, on an enlarged scale, of the awning of Figure 1 in a partially retracted position;

Figure 5 is an inside view of the upper fixed top panel section with the side channels removed and with the intermediate and lower top panel sections removed;

Figure 6 is a sectional view, on an enlarged scale, taken substantially along line VI—VI of Figure 5;

20 Figure 7 is a sectional view, on an enlarged scale, taken substantially along line VII—VII of Figure 4;

Figure 8 is a diagrammatic illustration of the cable and pulley operating means for the control arm;

25 Figure 9 is a sectional view, on an enlarged scale, taken substantially along line IX—IX of Figure 3;

Figure 10 is a sectional view, on an enlarged scale, taken substantially along line X—X of Figure 3;

30 Figure 11 is a sectional view, on an enlarged scale, taken substantially along line XI—XI of Figure 1;

35 Figure 12 is a sectional view, on an enlarged scale, taken substantially along line XII—XII of Figure 1;

Figure 13 is a sectional view, taken substantially along line XIII—XIII of Figure 12;

40 Figure 14 is a sectional view, taken substantially along line XIV of Figure 1;

Figure 15 is a sectional view, on an enlarged scale, taken substantially along line XV of Figure 1;

45 Figure 16 is a sectional view, on an enlarged scale, taken substantially along line XVI of Figure 1; and

Figure 17 is a sectional view, on an enlarged scale, taken substantially along line XVII of Figure 1.

50 As shown on the drawings:

In general, an awning constructed in accordance with the principles of the present invention may include an upper louvered top panel generally designated by reference numeral 20 arranged to be affixed to and extend outwardly

3

and downwardly from a wall, or upper portion of a window or door frame. A pair of fixed opposed allochiral side panels 21 and 22 are secured at their upper edges to the top panel 20 and are secured at their inner edges to the wall or side members of the window or door frame. An intermediate louvered top panel section 23 is pivoted or hinged at its normally upper edge to the lower edge of the upper fixed top panel 20 and a lower louvered top panel section 24 is pivoted or hinged at its normally upper edge to the normally lower edge of the intermediate top panel section 23. A pair of triangulate intermediate opposed side panels 25 and 26 are pivoted adjacent lower vertex portions thereof to the fixed side panels 21 and 22, respectively, adjacent the lower ends thereof, and a pair of lower generally triangulate opposed side panels 27 and 28 are pivoted adjacent lower vertex portions thereof to the fixed side panels 21 and 22. The lower pivoted side panels 27 and 28 are pivoted adjacent outer lower points thereof to the lower top panel section 24 adjacent the lower edge thereof.

With the construction thus far described, movement of the intermediate top panel section 23 about its pivotal connection to the fixed top panel section 20 will move the parts of the awning between extended position as illustrated in Figure 1 and compact retracted or folded position as illustrated in Figure 2. The movement of the top panel sections 23 and 24 and the movement of the pivoted side panel sections 25, 26, 27 and 28, when the awning is actuated between retracted and extended positions, will be clear from reference to Figure 4 which shows the parts in partially retracted or intermediate positions.

To operate the awning between retracted and extended positions, a shaft 30 is journaled for rotation below the upper fixed top panel sections. This shaft 30 projects outwardly beyond the sides of the fixed top panel section 20 and affixed to each of the projecting ends of the control shaft 30 is an operating arm 31. Each arm 31 is preferably fixed to the shaft 30 by means of a cap 32 which extends over the end of the shaft 30, and each operating arm extends through the associated cap 32 and the associated end portion of the shaft 30 and suitably anchored by a cotter pin 33 extending through each cap 32 and the end portion of the associated arm 31.

Telescopically associated with each of the arms 31 is a sleeve 34 having its outer end pivotally connected to the intermediate pivoted top panel section 23, preferably at the axis of pivotal connection between the top panel sections 23 and 24.

Referring to Fig. 4, it will be readily seen that rotation of the shaft 30 and arm 31 in a counter-clockwise direction will move the awning from extended to retracted position, the sleeve 34 being telescopically movable with respect to the arm 31 so that the spacing of the axes of the shaft 30 and the pivotal connection between the top panel section 23 and the top panel section 20 will not interfere with the pivotal movement.

To rotate the shaft 30 and move the awning between retracted and extended positions, a beveled sector gear 35 is affixed to a central portion of the shaft 30 and a beveled sector gear 36 rotatable about an axis normal to the axis of shaft 30 meshes with the sector gear 35. A control or actuating arm 37 is affixed to the beveled sector gear 36. This control arm 37 has a pair of pulleys 38 and 39 rotatably mounted on the free end thereof so that the control arm can be

4

readily operated by rope, cable, or the equivalent.

Figure 8 diagrammatically illustrates a preferred rope and pulley operating arrangement for the control arm 37. Referring thereto, a pair of pulley blocks 41 and 42 are secured to the side panel 21 and a pulley block 43 is secured to the side panel 22. A rope or cable 44 is secured at one end to the side panel 21 by means of an eyelet 45 and is secured at its other end to the side panel 22 by means of an eyelet 46. The cord 44 extends from the eyelet 45 around the pulley 38, around the pulley 42, downwardly to a looped end 44a forming operating portions 44b and 44c, and from the portion 44a upwardly around the pulley 41, over to and around the pulley 43, around the pulley 39 and to the eyelet 46.

It will be readily seen that a downward pull on the portion 44b will shorten the length of the cord 44 between the pulley 38 and the side panel 21 so that the operating arm 37 will be moved counterclockwise as viewed in Fig. 8. Conversely, a downward pull on the portion 44c will shorten the length of the cord 44 between the pulley 39 and the side panel 22 and will move the operating arm 37 clockwise as viewed in Fig. 8. Movement of the control arm 37 counterclockwise as viewed in Figure 8 will operate the control shaft 30 to move the awning to extended position and clockwise movement of the control arm 37 will operate the control shaft 30 to move the awning to retracted position. To secure the awning in either retracted or in extended position, the looped end portion 44a may be secured to a cleat 47 as illustrated in Figures 1 and 2.

Having thus described the general construction and operation of the awning, the construction and assembly of the various parts of the awning will now be described in detail.

An elongated bar or bracket 50 having an angular, generally L-shaped cross-section is adapted to be secured to the upper portion of the window frame or the like. This bracket 50 preferably has inverted keyhole openings 51 adjacent the ends thereof facilitating the disposition of the bracket over heads of screws extending into the upper portion of the window frame, as best illustrated in Fig. 5. A pair of bars 52 and 53 are affixed to the end of the bracket 50 and extend outwardly and downwardly therefrom. The bar 52 has a flange portion 52a extending upwardly from the outer edge thereof and a flanged portion 52b extending downwardly from the inner edge thereof and the bar 53 has a flange 53a extending upwardly from the outer edge thereof and a flange 53b extending downwardly from the inner edge thereof, as best illustrated in Figs. 5, 11 and 14.

To secure the bars 52 and 53 to the bracket 50, the bracket 50 has downwardly turned ears 54 and 55 at the ends thereof which are secured to the upwardly extending flanged portions 52a and 53a of the bars 52 and 53, respectively, by means of rivets 56. The down-turned flange portions 52b and 53b are secured to the upper edge portions of the fixed top panels 21 and 22, respectively, by means of rivets 57 or equivalents as seen in Figs. 3, 4, and 6.

An upper louver 60 is formed with an upturned flange portion 60a at its inner edge so that the louver fits snugly against the bracket 50. The louver 60 is herein secured to the bracket 50 by means of rivets 61 as shown in Fig. 5. The outer portion of the louver 60 is held in spaced relation to the bars 52 and 53 by means of spacers 62 secured to the louver 60

and the bars 52 and 53, preferably by means of a riveting operation.

A plurality of louvers 63 are secured between the bars 52 and 53 and extend outwardly and downwardly in overlapping relation. To secure the louvers 63 to the bars 52 and 53, the bars 52 and 53 are deformed upwardly to provide stepped portions 52c and 53c, respectively, against which rearward portions of the louvers 63 are secured by means of rivets 64. The bars 52 and 53 are further deformed to provide stepped portions 52d and 53d, respectively, to which spacers 65 are secured, the upper ends of the spacers 65 being secured to the forward portions of the louvers 63 by means of a riveting operation. This construction is best illustrated in Fig. 6. Referring thereto, it may be noted that the downturned flanged portions 53b may be cut out as at 66 so that the stepped portions 53c and 53d may be more readily formed.

The louvers 63 are preferably disposed in overlapping relation as illustrated so that air can readily pass between the louvers while rain, snow and the like are effectively excluded. To further prevent rain, snow and the like from passing between the louvers, each louver 63 is preferably formed with an upwardly extending flanged portion 63a at its rearward side and downwardly extending flanged portion 63b at its forward side.

As stated above, the operating mechanism is carried by the upper fixed section of the awning and with reference to Figs. 3, 4 and 5 it will be seen that the control shaft 30 is journaled for rotation in bearing plates 66 secured to the outer sides of fixed panels 21 and 22 and the downturned flanges 52b and 53b by means of rivets 67.

The sector gear 35 is affixed to the shaft 30, and the sector gear 36, to which the control arm 37 is affixed, is journaled for rotation on a support bracket 70 through which the shaft 30 extends. The bracket 70 has a portion extending between the flanges of a channel 71 and is secured thereto by means of rivets or bolts 72. The channel 71 extends upwardly and inwardly and is secured at its upper end to the bracket 50 by means of a screw 73. To provide central support for the louvers 63, a centrally located angularly formed plate 75 is secured at its upper end to the channel 71 by means of a rivet 76 and to central portions of the louvers 63 by means of rivets 77 as best illustrated in Fig. 3.

To prevent rain, snow and the like from entering at the sides of the top panel section 20, and to rigidify the top panel section 20, a channel 78 is attached to the up-turned flange 52b by means of rivets 79 and extends over the left ends of the louvers 63, as viewed in Fig. 1 and a channel 80 is secured to the up-turned flange 53b by means of rivets 81 and extends over the right-hand ends of the louvers 63. The channels 78 and 80, for the purpose of clarity of illustration, have not been shown in Fig. 5, but may be readily seen in Figs. 1, 2, 3, 4, 11 and 14.

The intermediate top panel section 23 is somewhat similar in construction to the affixed top panel 20 described above. Referring to Figs. 3 11, 12 and 15, louvers 83 are secured between brackets 84 and 85 of generally right-angular cross-section, the brackets 84 and 85 having upwardly deformed stepped portions 84a and 85a, respectively, to which the louvers may be secured by means of rivets 86 and spacers 87. A pair of channels 88 and 89 are attached to the brackets 84 and 85, respectively, and extend

over the louvers 83 to prevent rain, snow and the like from entering between the louvers from the sides.

To hinge the intermediate side panels section 23 to the upper affixed panel section 20, brackets 91 having spaced ears 91a and 91b are fixed to the up-turned flanges 52a and 53a by means of rivets 92 and plates 93 having ears 93a are connected to the brackets 84 and 85 by means of rivets 94. Hinge pins 95 extend through associated ears 91a, 93a and 91b. Thus, the intermediate top panel section 23 is hinged to the affixed top panel section 20 so that it may be moved between the positions of Figs. 1 and 2. If desired, in order to provide further support for the louvers 83 of the intermediate top panel section 23, a plate 96 having a generally angular configuration may be secured to the louvers 83 intermediate the sides thereof by means of rivets 97, as best illustrated in Fig. 3.

The lower top panel section 24 is constructed somewhat similarly to the sections 20 and 23 described above. Referring to Figs. 3, 12, 13 and 16, louvers 100 are arranged between side L-shaped brackets 101 and 102, the brackets 101 and 102 having upwardly deformed stepped portions 101a and 102a, respectively, to which rear portions of the louvers 100 are connected by means of rivets 103 and to which forward portions of the louvers 100 are secured by means of spacers 104. Further support of the louvers 100 may be provided, if desired, by means of a plate 105 having an undulating angular configuration located centrally between the brackets 101 and 102 and to which the louvers may be connected by means of rivets 106 as illustrated in Fig. 3.

To pivotally connect the top panel section 24 to the top panel section 23, a bracket 107 having spaced ears 107a and 107b is secured to each of the brackets 84 and 85 by means of rivets 108, a plate 109 having an ear 109a extending between the ears 108a and 108b is fixed to each of the brackets 101 and 102 by means of rivets 110 and a hinge pin 111 extends through the ears 108a, 109a and 108b. The hinge pins 111 also serve as pivotal connections for the telescoping arms 34, as shown in Fig. 4.

The top panel section 24 has a lower valence portion including a pair of plates 112 and 113 mounted on the brackets 101 and 102, respectively, by means of rivets 114. A plate 115 extends between the plates 112 and 113, the plate 115 having a terminal flange 115a secured to the plate 112 and a terminal flange 115b secured to the plate 113.

To further rigidify the top panel section 24 and to prevent rain, snow, or the like from entering at the sides of the louvers 100, a channel 116 is disposed around the sides and lower edge of the section 24. The channel 116 has a portion 116a connected to the bracket 101, a portion 116b connected to the flanged portion 115c of the plate 115 and a portion 116c attached to the bracket 102.

By this invention, an interlock is provided between the lower top panel section 24 and the side panels 27 and 28 in the open or extended position of the awning. To this end, generally L-shaped brackets 119 and 120 are mounted on the side panels 27 and 28, respectively, adjacent the outer edges thereof.

Referring to Fig. 16, the bracket 119 has a generally V-shaped deformation 119a therein into which an integral generally V-shaped pro-

jection 101b of the bracket 101 extends in the open or extended position of the awning. Similarly, as shown in Figures 12 and 13, the bracket 120 has a generally V-shaped trough-like projection 120a therein into which an integrally formed generally V-shaped projection 102b of the bracket 102 extends in the open or extended position of the awning. Thus, an interlocking engagement is provided between the side panels 27 and 28 and the top panel section 24.

To pivotally connect the top panel section 24 to the side panel sections 27 and 28, with reference to Figs. 12 and 17 it will be seen that a pair of brackets 121, each having a pair of inwardly extending ears, are secured to the plate 115, an ear 122 is attached to each of the plates 119 and 120 and a hinge pin 123 extends through the ears of each of the brackets 121 through each of the ears 122.

To rigidify the side panels 21, 22, 25, 26, 27 and 28, in-turned flanges are formed at the inner and outer edges of each of the panels. If desired, the side panels may be further rigidified to deaden the same against vibrations that might be caused by variations in wind pressure, for example, by means of strips 125, preferably of wood, fixed in place adjacent the outer flanged edges of side panels 21 and 22, strips 126 adjacent the outer flanged edges of panels 25 and 26 and strips 127 adjacent the outer flanged edges of side panels 27 and 28.

The panels 25 and 27 are pivoted to the panel 21 and the panels 26 and 28 are pivoted to the panel 22 by means of generally U-shaped brackets 128 mounted on the side panels 21 and 22. Referring to Fig. 7, a pin 129 extends through the legs of the U-shaped bracket 128 and through the panels 21, 25 and 27 and the strips 125, 126, 127 secured thereto. The pin 129 may be held in position by means of a cotter pin 130 as illustrated. To hold the panels in spaced relation, the panels 25 and 27 may have outwardly deformed portions 131 and 132, respectively, adjacent the opening therein through which the pin 129 extends. A similar bracket 128, pins 129 and cotter pins 130 are used to pivotally support the side panels 26 and 28.

As seen in Fig. 3, means are herein provided for guiding the panels 25, 26, 27 and 28 in their pivotal movement between retracted and extended positions. To this end, a plate or bar 133 having a generally arcuate upper edge is pivotally connected to each of the panels 21 and 22 by means of a pin 134. Referring to Figs. 3 and 9, each bar 133 has a transverse slot 135 in the inner end portion thereof and a headed pin 136 extends through each of the slots 135 and is connected to the associated side panel 21 or 22. On each side of the awning, a tension spring 137 has one end connected to the end of the bar 133 and the other end attached to the associated side panel 21 or 22 to resiliently urge the bars upwardly. As best illustrated in Figure 10, a headed pin 138 is secured to each of the pivoted side panels 25 and 26 and extends over the upper arcuate edge of the associated bar 133. It will be readily seen that the engagement between each of the pins 138 and the associated bar 133 will maintain the side panels 25 and 26 in position during pivotal movement between retracted and extended positions, the tension springs 137 acting to resiliently engage the pins 138 with the bars 133 during the pivotal movement.

To guide the side panels 27 and 28, a plate 139

is mounted on each of the panels 25 and 26, each plate having an upper portion 139a inwardly spaced from the inner face of the associated panel 25 or 26 and having an arcuate upper edge. A headed pin 140 is secured to each of the panels 27 and 28 and engages the upper arcuate edge of the associated plate 139 to guide the panels 27 and 28 in their movement between retracted and extended positions.

In summary, the awning of this invention, being constructed of metal, is strong and durable as contrasted with the flimsily constructed conventional awnings which wear out quickly. The parts of the awning are readily constructed and assembled and may be smoothly actuated between folded and extended positions. It will be noted that the parts snugly engage and interlock in both positions so that rattling and noise are effectively prevented. In addition, the awning presents a neat and attractive appearance in both extended and folded positions.

Further, the component parts of the awning are in the main simple stampings, simply connected, whereby the awning is economically manufactured.

It will be understood that modifications and variations may be effected without departing from the spirit and scope of the novel concepts of the present invention.

I claim as my invention:

1. An awning comprising a fixed top panel, a plurality of hingedly connected top panels foldable over the fixed top panel, an actuating arm, and gear means connecting the actuating arm and the foldable top panels together.

2. An awning comprising a fixed top panel, a pair of fixed side panels secured to the fixed top panel, a plurality of hingedly connected top panels foldable over the fixed top panel, a plurality of side panels pivoted on a common axis and retractable to nested positions between the fixed side panels, and means connecting the retractable side panels and the foldable top panels together for concurrent actuation thereof.

3. An awning comprising a fixed top panel and a pair of movable top panels hingedly connected thereto, the movable top panels being actuatable between an extended position and a compact folded position over the fixed top panel, a pair of fixed side panels secured to the top panel, a pair of movable side panels pivoted on each of said fixed side panels, each movable side panel being actuatable between a retracted position in nested relationship with the associated fixed side panel and an extended position in which an edge portion thereof engages and supports one of the movable top panels.

4. An awning comprising a fixed top panel and a pair of movable top panels hingedly connected thereto, the movable top panels being actuatable between an extended position and compact folded position above the fixed top panel, an operating arm connected to one of said top panels for actuation thereof, and rope and pulley means for operating the actuating arm.

5. An awning comprising a plurality of hingedly connected top panels actuatable between extended position and compact folded position, an operating arm connected to one of said top panels for actuation thereof, a rope and pulley actuated control arm, and gear means operatively connecting the control arm and the operating arm.

6. An awning comprising a plurality of hingedly connected top panels actuatable between extended positions and compact folded positions,

and a pair of side panels pivoted on a common generally horizontal axis and hinged to a terminal one of said foldable top panels, said side panels supporting said terminal one of said top panels in the extended position thereof.

7. An awning comprising a plurality of hingedly connected top panels actuatable between extended positions and compact folded positions, a pair of pivoted side panels hinged to a terminal one of said top panels and supporting said terminal one of said top panels in the extended position thereof, and interlock means between said side panels and said terminal top panel.

8. In an awning having a foldable top and a plurality of relatively movable parallel pivotally connected side panels operatively associated with the foldable top, means for guiding one side panel in its pivotal movement relative to another side panel, comprising, a member connected to said another side panel and having an edge extending generally in an arc about the axis of pivotal connection of said one side panel and said another side panel, and a headed guided member affixed to said one side panel and engaging said arcuately extending edge to maintain said one and said another side panels in parallel relationship during relative pivotal movement thereof.

9. An awning comprising a first plurality of pivotally connected side panels relatively movable in generally parallel vertical planes, a second plurality of pivotally connected side panels relatively movable in generally parallel vertical planes and laterally spaced from said first plurality of side panels, and a foldable top operatively associated with said first and second pluralities of side panels.

10. In an awning having a movable top and a plurality of relatively movable parallel pivotally connected side panels operatively associated with the foldable top, means for guiding one of said side panels in its pivotal movement relative to another side panel, comprising: a member pivotally connected to said another side panel and having an edge extending generally in an arc about the axis of pivotal connection of said one and said another side panels, a guide member secured to said one side panel and engageable with said arcuately extending edge, and spring means between said pivotal member and said another side panel for resiliently urging said arcuately extending edge into engagement with said guide member to maintain said one and said another side panels in parallel relationship during relative pivotal movement thereof.

11. An awning comprising first and second vertical, laterally spaced trianguloid affixed side panels having upper edge portions disposed in an

inclined plane, first and second pluralities of vertical trianguloid side panels pivotally connected adjacent lower portions thereof to said first and second fixed side panels, respectively, said first and second pluralities of pivotal side panels being actuatable between retracted positions in nested relationship with said fixed side panels and extended positions in which edge portions thereof are aligned with and extended downwardly from said upper edge portions of said fixed side panels, and a foldable top operatively associated with said side panels and actuatable therewith to abut the aligned edge portions thereof.

15 12. An awning comprising a foldable top including a fixed top panel section and a pair of movable top panel sections hingedly connected thereto, the movable top panel sections being actuatable between extended positions in alignment 20 with the top panel section and folded position in nested relationship to the fixed top panel section, and actuation means comprising a shaft journaled for rotation below the fixed top panel section, an actuating arm carried by said shaft, 25 a member telescopically connected to said actuating arm and pivotally connected to one of said movable top panel section, a first beveled sector gear carried by said shaft, a control arm, a second beveled sector gear carried by said control arm and meshing with said first sector gear, and rope and pulley means for operating said control arm.

30 13. An awning having a foldable top comprising a plurality of hingedly connected top panel sections actuatable between extended and compact folded position, each top panel section including a pair of side members and a plurality of louvers supported therebetween in overlapping relation, the louvers adjacent hinged connections of adjacent sections being in overlapping relation 35 in the extended position of the top panel sections thereby to prevent entrance of rain and the like through the extended top.
